ATTORNEYS

UNITED STATES PATENT OFFICE.

JOHN A. WATTS, OF MILFORD, PENNSYLVANIA.

SILENT POLICEMAN.

Application filed April 23, 1923. Serial No. 634,091.

To all whom it may concern:

Be it known that I, JOHN A. WATTS, a citizen of the United States, and a resident of Milford, in the county of Pike and State 5 of Pennsylvania, have invented a new and Improved Silent Policeman, of which the following is a full, clear, and exact description.

This invention relates in general to signal 10 devices and more particularly to an improvement in street traffic indicating devices of the type known as "iron men" or "silent policemen" and forming the subject-matter of my prior Patent No. 1,267,021, 15 dated May 21, 1918.

The object of the invention is to provide a device of this character having all of the advantages and capacities of the construction forming the subject-matter of my 20 prior patent above referred to and wherein at the same time all of the parts of the device are readily accessible and removable for purposes of adjustment, replacement and repair, wherein parts of the device are 25 adjustably mounted so that the desired position of the signal thereof may be had at all times, and wherein the flexible securing device is positively and securely fastened to the bracket utilized to mount it on the 30 base.

Other objects and advantages of the invention reside in certain novel features of the construction, combination and arrangement of parts which will be hereinafter more 35 fully described and particularly pointed out in the appended claims, reference being had to the accompanying drawings forming part of this specification, and in which:

Figure 1 is a view, partly in section and 40 partly in elevation, showing the preferred embodiment of the invention;

Figure 2 is a plan view of the base alone;

Figure 3 is a fragmentary detail view in 45 enlarged vertical section on line 3—3 of Figure 1.

Referring to the drawings, the numeral 10 designates a base member which comprises a hollow truncated cone constructed of cast iron or the like. A legend-bearing or signal device 11 is provided and is preferably of 50 light sheet metal. The signal device 11 has its upper end rotatably mounted upon a longitudinally extending rigid member 14. The lower end of the rigid member 12 extends 55 below the lower end of the signal

device 11 and is received in the upper end of a transversely flexible or yieldable supporting device 12. This supporting device 12 may comprise one or more concentrically wound coil springs. 60

The construction and arrangement thus far described is identical with that shown in my prior patent above referred to, except that the interior of the truncated cone constituting the base is made smooth in the invention forming the subject-matter of this application whereas lugs were provided thereon in the invention forming the subject-matter of the said patent. 65

The present invention has to do particularly with the means for mounting the supporting device 12 on the base member 10; and for this purpose a bracket 16 is provided and preferably comprises a tubular member having one end open and provided with an outwardly extending annular flange 17 and having its outer end closed by an end wall 18. The main portion of the tubular member includes a cylindrical section 19 constituting a socket and an enlarged or flaring section of frusto conical form which is designated at 20. The top of the base member 10 is formed flat and smooth and is arranged to lie in a plane parallel to the bottom of the plane of this 70 base member. In the assembly the flange 17 rests on the flat top of the base member and the bracket 16 depends into the space defined and enclosed by the hollow base member with the lower end wall 18 lying near 75 to the bottom of the base member. The lower end of the coil spring constituting the flexible supporting device 12 is fitted in the socket 19 of the bracket 16. The lowermost convolution of the coil spring constituting the flexible supporting device 12 has a portion extended angularly or radially of the coil, as indicated at 22, and the terminal end of such portion is then bent or extended axially of the coil spring, as indicated at 21. The axially extending terminal 80 85 90 95 100 105 110

21 projects through an opening 23 provided in the end wall 18 of the bracket 16. The extremity of the axially extended terminal 21 is externally threaded and has a nut 24 engaged therewith, the nut 24 coating with the end wall 18 of the bracket and with the externally threaded terminal 21 to hold the lower end of the coil spring constituting the supporting device 12 in its socket 19. 110

For positively securing the bracket 16 to the base member fastening devices, such as bolts 25, are employed, these bolts 25 passing through bolt holes in the flange 17 and being threaded into bolt holes or sockets provided therefor in the top of the base 10. Of course the heads of the bolts 25 engage the flange 17. These bolts also permit of adjustment of the bracket on the base member so that the axis of the bracket and of the supporting device 12 and signal device 11 may be maintained in the vertical even though the base lie at a slight angle to the horizontal since any one or more of the bolts 25 may be loosened and U-shaped or semi-circular shims inserted between the flange 17 and the top of the base member 10.

With the device thus constituted there is provided a heavy base having a relatively large bottom and upwardly and inwardly extending sides terminating in the relatively large opening in the top thereof. A base having these characteristics in conjunction with a light signaling device 11 and means for mounting the lower end of the flexible supporting device 12 at a point close to the bottom of the base provides a very staple structure not liable to be overturned and well adapted to withstand collision or the like. The provision of the enlarged section 20 on the bracket member 16 provides a clearance to accommodate the movements of the transversely flexible supporting device 12, so that this supporting device will not engage the base member adjacent the top thereof even when deflected by virtue of the collision of a vehicle therewith. The positive and secure fastening or attachment of the transversely supporting member 12 to the bracket member 16 prevents disassociation of these parts. Moreover the bracket member and consequently the supporting device 12 and signaling device 11 may be readily taken from the base without lifting the base from the ground by simply removing the bolts 25 and lifting the bracket member from the base, the base being permitted to remain in position on the street or roadway. It is to be noted also that the base 15 defines an enclosed and protected space into which the bracket member 16 depends.

I claim:

1. In a device of the character described, a hollow base of frusto-conical form, a signal device, a transversely flexible supporting device connected to the signal device, and means for mounting the supporting device on the base including a tubular bracket member having its upper end open and provided with an outwardly extending annular flange adapted to rest on the top of the frusto-conical base, the lower end of the tubular bracket member being closed and being disposed within the frusto-conical base and adjacent the bottom thereof, said tubular bracket member having a portion constituting a socket and an enlarged portion providing a clearance, the transversely flexible supporting device having its lower end received and secured in said socket and having a portion adapted to operate in the clearance provided by the enlarged portion of said tubular bracket member, and releasable fastening means for adjustably securing the flange to the top of the base.

2. In a device of the character described, a base adapted to rest on a roadway or the like and having a relatively large bottom and also having a relatively large opening in the top thereof, said base defining an enclosed space above the roadway, a signal device, a coil spring having its upper portion connected to the signal device, and means for mounting the lower end of the coil spring on the base including a tubular bracket member removably secured to the top of the base and depending into the space enclosed thereby, the upper end of the tubular bracket member being open and the lower end of the tubular bracket member being closed, the lower end of the coil spring being seated in said bracket member and having its lower convolution inwardly extended, the terminal of the lower convolution being axially extended with respect to the coil spring, the lower closed end of the bracket member having an opening receiving said axially extending terminal and a nut threaded on the terminal and engaged with the bracket member for holding the coil spring to the bracket member.

JOHN A. WATTS.
